CASE FOR A CHECK ENCODER

James W. Jacobson, St. Nom la Breteche, France, and Richard G. Clayton, Detroit, and Jerry J. Sims, Southfield, Mich., assignors to Burroughs Corporation, Detroit, Mich.

Continuation-in-part of design application Ser. No. 395,234, Sept. 7, 1973. This application Mar. 6, 1975, Ser. No. 555,955

Term of patent 14 years
The term of this patent subsequent to Feb. 3, 1990,
has been disclaimed

Int. Cl. D14—02
U.S. Cl. D64—11 C

FIG. I.

FIG. 2.

FIG. 1 is a front perspective view of a case for a check encoder showing our new design; and

FIG. 2 is a rear perspective view thereof.

This is a continuation-in-part of design application Ser. No. D. 395,234, filed Sept. 7, 1973.

We claim:

The ornamental design for a case for a check encoder, substantially as shown.
